Patented Apr. 26, 1921.

UNITED STATES PATENT OFFICE.

JOHN EMANUEL JOHNSON AND CHARLES H. OSLUND, OF WORCESTER, MASSACHUSETTS, ASSIGNORS TO THE C. & J. MACHINE COMPANY, OF WORCESTER, MASSACHUSETTS, A CORPORATION OF MASSACHUSETTS.

LABEL-PICKING DEVICE.

1,876,097.

Specification of Letters Patent. Patented Apr. 26, 1921.

Application filed March 21, 1919. Serial No. 283,963.

To all whom it may concern:

Be it known that we, JOHN EMANUEL JOHNSON and CHARLES H. OSLUND, citizens of the United States, residing at Worcester, in the county of Worcester and State of Massachusetts, have invented a new and useful Label-Picking Device, of which the following is a specification.

This is an improvement over, and in part a continuation of, our allowed and forfeited application Serial No. 125,268, filed October 12, 1916.

This invention relates to a mechanism for transferring labels from a label holder to a bottle or other article to be labeled, and applying them thereto, and while capable of general use is particularly adapted for use with short labels. It is also adapted to be used where it is desired to paste over so much of the surface of the labels that for that reason pickers come too close together for operation in the ordinary manner.

The principal objects of this invention are to provide a construction in which, when the pickers come closer together than the thickness of the bottle, provision is made for enabling them to move out of the way in a simple and convenient manner; to provide means whereby the pickers are yieldingly brought back to normal position after the bottle has passed between them, means for permitting elements of the label holder to pass through the picker when it strikes the same, a durable and effective construction for the picker springs and connected parts, and other features as will appear.

This invention is designed as an improvement over the matter shown in Figures 34 to 37 of our Patent No. 1,238,713, patented August 28, 1917, but can be used independently thereof.

Reference is to be had to the accompanying drawings, in which—

Fig. 1 is an elevation of a label applying device constructed in accordance with this invention;

Fig. 2 is an edge view of the same with parts in section on the line 2—2 of Fig. 1;

Fig. 3 is a front elevation of one of the picker supporting members;

Fig. 4 is a horizontal sectional view on the line 4—4 of Fig. 1;

Fig. 5 is a horizontal sectional view on the line 5—5 of Fig. 1;

Fig. 6 is a vertical sectional view on the line 6—6 of Fig. 3, and

Fig. 7 is an elevation of a detail.

This invention is shown as used in connection with a movable bottle support 10 which carries the bottles supported in vertical position upon it and moves forward horizontally, as indicated by the arrow in Fig. 4. This is preferably a rotatable support but can move in any other direction.

In this case, a horizontal rod 12 extends over the support 10 and carries a sliding sleeve 13. This sleeve is keyed to turn with the rod 12 and is adapted to be operated as in our above identified patent by means of a lever 16 oscillating on an axis below the bottom of the elements shown in Fig. 1, and driven in any desired way. It is to be understood that with the elements indicated in these drawings this sleeve 13 slides back and forth on the rod, and is also capable of swinging about the rod for the purpose of taking the labels from a label holder not shown.

On this sleeve are a pair of bottom projections 15 to which are affixed the picker supports 17. These picker supports are rigidly connected with the sleeve 13 and will partake of all of its movements. The manner in which they are connected with it is shown more specifically in Fig. 2, but need not be described in detail.

On these supports 17 are mounted two pairs of pickers 19 and 20, shown as integral parts of a plate for the body labels and neck labels respectively. It is to be understood that paste is applied to what is the front surface of these pickers in Fig. 1 by a roller rolling along these surfaces, and that the pickers then turn on the rod 12 to take labels, as for example, those shown by dot and dash lines, from a pair of label holders not shown. They then swing back into a position in which the surfaces of the pickers are parallel with the axis of the bottle to which the labels are to be applied, in this case into a vertical position. Then the sleeve 13 with these pickers slides in the plane of the pickers over into a position in front of an approaching bottle. This is accomplished by the movement of the lever 16. This brings the pickers into the position shown in Fig. 1 and in full lines in Fig. 4, the labels A and B being located in position for

the bottle to take them up as it moves between the pickers.

The pickers are mounted on a vertical shaft 21 by means of hinges 22. For the purpose of yieldingly bringing them back into the position shown in full lines in Fig. 4 against stops 23 carried by the supports 17, springs 24 are used extending upwardly along vertical grooves in the front of these supports and means is provided extending through perforations 25 therein. The springs are fixed to hooks 26 located higher in the backs of these supports. It is to be noted that these supports are of channel form so as to provide strength and a place for receiving these springs.

These springs and their connections constitute an important feature of this invention. They are arranged vertically but act to swing the picker plates about vertical axes. This is desirable because the supports 17 are long and narrow, and it is not desirable to have any spring supporting arms projecting from them. We have devised this arrangement to avoid that and to insure a long life for the springs. The channel in the front of each support is utilized as a guide for a slide 27. One end of the slide receives the end of the spring, and the other end the hook end of a wire connector 28 which passes through the perforation 25. The wire 28 is pivoted to a plate 32 on the picker plate 19 at a distance from the vertical shaft 21 on which the plate 19 is pivoted. Therefore the spring 24 yieldingly holds the slide 27 up and tends to swing the plate 19 back into contact with the stops 23.

It will be noted also that the picker plates 19 are provided with perforations 29. These are so located as to receive the hooks of the label magazines which hold the edges of the label. Such hooks are indicated in our above identified patent. In this way, the pickers are adapted to receive the edges of the label well within their own edges so that the label is provided with a relatively large pasted area on account of coming into contact with a great surface of the picker plate 19 itself, which, of course, is covered with paste. This is an important advantage because in the ordinary constructions the label had to be of the same shape substantially as the picker plate, or at least the same shape at its edge in order to be capable of being taken from the label holder by it.

Another feature shown here consists in the provision of projections 30 mounted on and extending beyond the edge of the picker 60 and projecting inwardly therefrom slightly for engaging the bottle and keeping the picker itself away from the surface of the bottle. This is advantageous when operating with short labels to avoid applying any 65 unnecessary paste to the bottle and to assist

in causing the label to be laid out smooth upon it.

It will be seen, therefore, that the label pickers are capable of swinging on axes of their own carried by these supports 17 and 70 are yieldingly pressed back so as to rest normally as near the bottle as possible against the stops 23 and to be brought back into this position after the bottle has forced them away from it as indicated in Fig. 4. 75

Although we have illustrated and described only a single form of the invention, we are aware of the fact that modifications can be made therein by any person skilled in the art without departing from the scope 80 of the invention as expressed in the claims. Therefore, we do not wish to be limited to all the details of construction herein shown and described, but what we do claim is—

1. The combination with a label picker 85 support, of a shaft thereon parallel therewith, means for supporting an article to be labeled in position parallel with said shaft and adjacent thereto, a label picker carried by said shaft and adapted to swing 90 thereon independently of said support, said support being of channel form, a spring connected with said picker, and means extending through said support to the rear side thereof and along the same for normally swinging the picker into operative position.

2. The combination with a label picker support having a shaft thereon, of a picker mounted to swing on said shaft, a spring 100 connected with the picker and support for yieldingly holding the picker in operative position, and a projection extending from the picker for engaging the article to be labeled and preventing contact of the picker 105 with said article.

3. The combination of a label picker support having a shaft thereon, of a picker mounted to swing on said shaft, a spring connected with the picker and support for 110 yieldingly holding the picker in operative position, and a projection extending from the picker for engaging the article to be labeled, and turning the picker back away from said article in opposition to said spring 115 as the bottle approaches labeling position.

4. The combination of a movable picker support adapted to move into operative position, a picker movably mounted thereon, means for movably supporting the bottle adjacent to the picker, and means movable with the support for engaging an approaching bottle and preventing the picker engaging said bottle.

5. In a label picking device, the combination of a pair of supports, a picker plate pivoted on each support, and a longitudinally extensible spring arranged on each support parallel with the axis of the pivot thereon and connected with the picker plate. 125 130

6. In a label picking device, the combination of a support, a picker plate pivoted thereon, a longitudinally extensible spring arranged on the support parallel with the axis of the picker plate pivot, and connected through the support with the picker plate to hold it yieldingly back in position to engage the article to be labeled.
7. In a label picking device, the combination of a support, a picker plate pivoted on said support, a longitudinally extensible

spring arranged on said support parallel with the axis of the picker plate pivot and connected with the picker plate, a slide movable on the support parallel with the length 15 of the spring and connected therewith, and a rigid member pivotally connected with said slide and with the picker plate.

In testimony whereof we have hereunto affixed our signatures.

JOHN EMANUEL JOHNSON.
CHARLES H. OSLUND.
